DISPOSABLE CONTAINER FOR AN ULTRASONIC NEBULIZER

Thomas W. Argy, Chicago, and Michael A. Fanizza,
Mount Prospect, Ill., assignors to Zenith Radio Corpora-
tion, Chicago, Ill.

Filed June 4, 1971, Ser. No. 149,977

Term of patent 14 years

Int. Cl. D23—01; D24—02

U.S. Cl. D83—1 N

FIG. 1

FIG. 2

FIG. 3

FIG. 4

FIG. 1 is a perspective view of our design of a disposable container for an ultrasonic nebulizer;

FIG. 2 is an elevational view of the right side thereof;

FIG. 3 is a top plan view thereof; and

FIG. 4 is a bottom plan view thereof.

We claim:

The ornamental design for a disposable container for an ultrasonic nebulizer, substantially as shown.
